UNITED STATES PATENT OFFICE

97,395

DESIGN FOR A RING OR SIMILAR ARTICLE OF JEWELRY

Felix P. Kinsley, St. Louis, Mo.

Application July 22, 1935, Serial No. 57,781

Term of patent 7 years

To all whom it may concern:

Be it known that I, Felix P. Kinsley, a citizen of the United States, residing at the city of St. Louis, State of Missouri, have invented a new, original, and ornamental Design for a Ring or Similar Article of Jewelry, of which the following is a specification, reference being had to the accompanying drawing, forming part thereof.

The drawing is a perspective view of a ring

showing my design. The dominating features of my design for a ring reside in the lancet-shaped cameo stone shown in full lines and in its relative position to the jewel settings also shown in full lines.

I claim:

The ornamental design for a ring or similar article of jewelry as shown and described.

FELIX P. KINSLEY.
